CLAIM

The ornamental design for a bag, as shown and described.

DESCRIPTION

FIG. 1 is a front perspective view of a bag showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the bag of FIGS. 1-7 with the pockets shown in an expanded state;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines in the areas between the lower panels and the body of the bag represent panel seams and form no part of the claimed design. The broken line defined areas and the unshaded regions therein representing the upper three flaps, the bottom of the bag, and the stripe on the front lower pocket form no part of the claimed design. The unshaded rear portion of the bag forms no part of the claimed design. The broken lines depicting the straps, rings, zipper pulls, and other elements on the remainder of the bag show features that form no part of the claimed design.
